UNITED STATES PATENT OFFICE.

WILLIAM A. BARNES, OF BRIDGEPORT, CONNECTICUT.

FIRE-ALARM ANNUNCIATOR.

SPECIFICATION forming part of Letters Patent No. 395,111, dated December 25, 1888.

Application filed March 1, 1888. Serial No. 265,812. (No model.)

To all whom it may concern:

Be it known that I, WILLIAM A. BARNES, of Bridgeport, Fairfield county, Connecticut, have invented a new and useful Improvement 5 in Fire-Alarm Annunciators, of which the following is a specification.

A fire or burglar alarm transmitted electrically over a line to a central station usually indicates a certain house, district, block, or 10 other locality, somewhere in which the disturbance of the circuit has occurred. In answering the call, the fire department or guard generally goes to the alarm-box, the number of which is automatically telegraphed, and reliance is placed upon subsequent direction to 15 find the exact point of the fire, for example.

In order thoroughly to protect a densely-populated quarter, it is necessary greatly to multiply alarm-boxes and to reduce the areas of 20 the several districts protected by each box. Otherwise serious delays may occur in locating a fire, even after relief has reached a box. In single buildings prompt and certain information of the point in the building at which 25 a fire has broken out or an improper attempt at entrance has been made is often very important. In a warehouse, for example, devoted to the storage of large quantities of goods in separate closed rooms it is exceedingly 30 desirable to know at once in which room or in which story the danger has occurred. So, also, in hotels and in apartment-houses, in many instances—as on board ship—access to all parts of the structure or 35 to the goods or cargo therein may be very difficult, and it then becomes of the last importance to be apprised as nearly as possible of the exact point of a fire, so that valuable time may not be lost in breaking out goods 40 or cargo not in the immediate vicinity of the danger.

My present invention is designed to show the position of the point at which the circuit has been disturbed within the general area 45 or district protected by the box. Thus, it will show a house in a certain block, for example, or the story or portion of a story in a house, or any particular locality or localities which it may be desired especially to distinguish. The operation of the indicating mechanism is automatic, and when it is combined

with automatic alarm mechanism, as herein illustrated, the same disturbance which determines the sending of the alarm likewise sets the indicating mechanism into action. 55

In order to insure rupture of the circuit by fire or by the increased surrounding temperature due to the proximity of fire, I propose to construct the branches 3 and 4 of the line, as hereinafter mentioned, of some fusible material, or preferably to employ the fusible conductor for which Letters Patent No. 378,078 were granted to me February 21, 1888. 60

My invention consists in the indicating mechanism, substantially as hereinafter set 65 forth.

In the accompanying drawings, Figure 1 is a front elevation and general view of the apparatus. In this figure, for the sake of clearness, the circuit-wires are omitted. They are 70 shown, however, and may be readily traced upon Fig. 2, which is a diagram or skeleton of the various connections. Fig. 3 is a view of the apparatus, showing the motor-gearing below the plate 38 in elevation and the parts 75 above said plate in section on the irregular line $\alpha\alpha$ of Fig. 1. Fig. 4 is a detailed plan view of a part of the indicator mechanism. Fig. 5 is a plan view, broken, of the under side of the rotary indicator-escapement disk 80 K. Figs. 6 and 7 show the circuit-closing device controlled by the door in two positions. Fig. 8 is a diagram which shows an arrangement of indicator-circuits in connection with 85 a building. Figs. 9, 10, 11, and 12 illustrate the operation of the escapement U and indicator-disk K. Fig. 13 is a detailed view of armature 11, plate 13, and spring 51. 90

Similar letters of reference indicate like parts.

At 1, 2, Fig. 2, is the main line divided into two branches, 3 4. Each branch 3 4 includes one of the coils of the differentially-wound magnet 5. This magnet, as shown in Fig. 1, is arranged in the box or case 6, which encloses the apparatus. Said box is provided with a hinged door, 7. The magnet is supported on the free end of a leaf-spring, 8, which is secured to the box or case at 9. Said spring has an upwardly-extending arm, 10, to which is pivoted the armature 11 of magnet 5. 12 is a standard, also supported

upon spring 8. Attached to said standard is a bar of hard rubber or other non-conducting material, 52, which carries a contact-plate, 13, and also a spring, 51, having on its lower side 5 a contact-point, 53, which spring is interposed between said armature and plate and normally holds the armature away from the pole of the magnet. At 14 is a hooked latch which is pivoted to bar 52, and which may be used, 10 when desired, to hold the armature 11, plate 13, and spring 51 in contact.

The ends of the coils of magnet 5 connect by wires 15 16, Fig. 2, with fixed spring-fingers 17 18. Between fingers 17 18 is another 15 fixed finger, 19, which, by means of wire 20, communicates with part 2 of main line.

21 is a disk of hard rubber or other non-conducting material, supported in front of the fixed plate 38 on a shaft, 39. Upon said 20 shaft is a winding-gear, 41, and a spring, 42. The end of the shaft is squared to receive a key, so that by rotating said shaft the spring 42 may be wound up. Adjacent to disk 21 is a fixed arm, 22, Fig. 1, and upon the face of 25 said disk are two pins, 23 and 24.

Normally the pin 24 makes contact with the upper edge of arm 22, and the pin 23 presses together the spring-fingers 17 18 19, and this 30 is the condition of the parts when the apparatus is ready for operation. Consequently (see Fig. 2) there will be a closed circuit from main line at 1 through branches 3 4 and magnet 5, to wires 15 16, to fingers 17 18, to finger 19, to wire 20, and to main line at 2.

35 25 is a spring-finger.

26 is another spring-finger, which is interposed between finger 25 and the periphery of disk 21. The end of finger 26 is bent or curved, as shown, to enter a recess in the periphery of 40 disk 21; hence, normally the fingers 25 and 26 are not in contact. Finger 25 connects with main line at 1 by wire 27. Finger 26 connects with main line at 2 by wire 20. Consequently said fingers 25 26 are in shunt 27 45 25 26 20 from main line.

The disk 21, as already stated, is rotated by the shaft 39 and spring 42. Geared to said shaft is an escapement-wheel, 28, Fig. 1, having an anchor, 29. To the anchor 29 is attached a rod, 30, which when held motionless causes one of the anchor-pallets to engage with the teeth of the escapement-wheel 28, and so to prevent motion of the latter, and hence of the disk 21.

50 55 On the end of rod 30 is a pin, with which engages a hook on the end of an arm, 31, which extends from the pivoted armature 32 of an electro-magnet, 33. One terminal of the coil of magnet 33 connects with armature 11 of magnet 5 by a wire, 34, Fig. 2. The other terminal connects by a wire, 35, with one pole of a local battery, 36. The other pole of said battery 36 connects by wire 37 with contact-plate 13 on bar 52. Therefore, included in 60 65 local circuit with battery 36 are wire 37, contact-plate 13, armature 11, wire 34, magnet 33, and wire 35.

I will now explain the operation of the apparatus so far as described. A current coming over the main line 1 and passing through the 70 oppositely-wound coils of magnet 5 obviously does not energize that magnet. Hence said current continues on through wires 15 and 16 to spring-fingers 17 18, finger 19, and wire 20, and so to line again at 2. Suppose now, however, that either branch, 3 or 4, be interrupted, or more resistance be interposed, or more current applied in one branch than in the other. Then, clearly, the coils of magnet 5 will no longer balance one another, and the 80 magnet under the influence of the predominating coil will be energized and consequently will attract its armature 11; but when the armature 11 is attracted it closes contact with plate 13, and so establishes local circuit through magnet 33. Magnet 33 then attracts its armature 32, and so causes arm 31 to release rod 30. Anchor 29 is then no longer held, and the escapement-wheel 28 and associated clock-train is free to operate, and hence to rotate the disk 90 21. Now, as the disk 21 (see Fig. 1) turns in the direction of the arrow the pin 23 thereon, which has been holding the fingers 17 19 18 in contact, is carried to the left, and these fingers, being of spring metal, separate. Therefore the circuit from main line at 1, magnet 5, wires 15 16, said fingers, wire 20, and main line at 2 is broken, and the magnet 5 is free 95 to release its armature again; but the clock-work, having now been started, goes on. As 100 the disk 21 rotates, the recess in its edge moves from under the end of finger 26, and this finger, now pressed upon by the circular part of the periphery, is so forced into contact with finger 25. Therefore, main-line circuit is closed through 1, 27, 23, 26, 20, and 2. On the edge of disk 21 are formed indentations arranged in any desired succession, as 105 shown in Fig. 1, into which the extremity of finger 26 descends as they move beneath it. 110 The disk 21 is therefore a circuit-breaking wheel interposed in the main circuit, and by its rotation making and breaking said circuit, so as to produce an alarm through any 115 well-known mechanism capable of being actuated in accordance with said interruptions at a distant point—as, for example, a central fire-station. To recapitulate, therefore, whenever the strength of the current on one branch, 3 or 4, of the main line becomes stronger than 120 on the other branch, the magnet 5 closes local circuit through magnet 33, which releases the clock-train, which then rotates the disk 21. When the disk 21 begins to rotate, the existing circuit from main line through the apparatus is broken and a new circuit is established, and this new circuit is interrupted in 125 some definite way by the action of the inequalities on the periphery of the revolving disk, so that an alarm is thus transmitted 130 over main line to a distant station, which alarm may serve in the usual way to indicate the location of the apparatus.

In combination with devices already de-

scribed I show herein an indicating mechanism, the object and purpose of which is to exhibit more definitely the location of the point of disturbance of the circuit, as aforesaid. 5 Thus, for example, the alarm transmitted as before described may give warning that the disturbance has taken place in a certain building. The indicating device would show to any one repairing to that building where- 10 about therein the disturbance originated—as, for example, on what floor or what room. Of course this same idea can be varied in a multiplicity of ways, so that, for example, the alarm might send the number of a block of 15 buildings and the indicator show the particular building; or the alarm-signal might give a district number and the indicator show in what part of the district, and so on. The apparatus hereinafter set forth is not modified in 20 any wise materially to suit any of these purposes or others of cognate character.

In Fig. 2 the connecting-wires which more particularly relate to the indicator system are represented by dotted lines for convenience 25 in recognition.

At A is a circular plate of hard rubber or other insulating material fixed in place upon the plate 38. Upon the face of plate A and disposed at equal intervals apart around its 30 circumference are pairs of elevated contact-pins B B', C C', D D', E E', &c. In Figs. 1 and 4 six pairs of these points are shown. In Figs. 2 and 8, for the sake of simplicity, but four pairs are indicated. It will be seen from 35 what follows that any desired number of such pairs of pins may be employed.

Through a central opening in plate A passes a shaft, L, which is rotated by the coiled spring I, Fig. 3, when said spring is wound up. This 40 is done by applying a key to the squared end of the shaft L. Any other mechanism for rotating the shaft L may, however, be employed, so that I do not limit myself to the particular device for the purpose above described. Se- 45 cured to shaft L is a circular disk, K, Figs. 3, 4, and 5, of metal, to the under side of which is secured a spring-finger, G. When the disk K is revolved, the spring-finger G makes contact successively with each of the contact-pins B' 50 B C' C, and so on, on the plate A. A small projection, H, on one side of the finger G bears directly upon the side of the contact-pin. (See dotted lines, Fig. 4.) Projecting downward from the under side of the disk K are as many 55 pairs of pins, N N' O O', &c., as there are pairs of pins, B B' C C'. The disk K, as will now shortly be seen, acts as an escapement-wheel, the spring I when wound tending to cause it to rotate and the escapement now to 60 be explained, allowing it to rotate only a certain distance at a time.

Referring now to Figs. 1 and 3, P is an electro-magnet having a pivoted bell-crank armature, Q, provided with a retracting-spring, J. 65 To one arm of said armature is connected the link R, which is also connected to a cross-bar, S, on the vertical shaft T, Fig. 3. The shaft

T is stepped in plate 40, passes through plate 38, and carries on its end an escapement, U, in the form of a mutilated hollow cylinder, which 70 is placed in proximity to the pins N' N O O' upon the rotary escapement-disk K. When the magnet P attracts its armature Q, motion is communicated to the shaft T to rotate the escapement U in one direction, and when the 75 magnet P releases its armature the escapement U turns in the other direction. The operation of the escapement U, in connection with the wheel or disk K, will be understood from Figs. 9, 10, 11, and 12. In Fig. 9 the pin 80 N has met the inner periphery of escapement U, and the disk K is thus prevented from turning. In Fig. 10 the escapement U has been rotated to the new position shown, releasing the pin N, and the pin N' meets its 85 outer periphery. In Fig. 11 the escapement U has been rotated back to its original position and the pin N' meets its inner periphery. In Fig. 12 the escapement is brought back to the position of Fig. 10, and both pins are 90 freed, the disk being now free to rotate by the action of the spring I until the leading pin of the next pair meets the inner periphery of escapement U, which is turned once more into the position shown in Fig. 9, when the 95 same operations are repeated.

Near the face of disk 21 are two fixed spring-fingers, V W. Finger W connects by a wire, a, Fig. 2, to wire 4, and so to local battery 36. Finger V connects by wire b to contact-pin B' 100 on plate A. Shaft L, which passes through plate A, connects by wire c with one end of the coil of magnet P, and the other end of said magnet-coil communicates by wire d with wire 35, and so with the other pole of battery 105 36. Therefore the above circuit proceeds as follows: from battery 36 to wire 37, to wire 4, to wire a, to finger W. Here the circuit is broken; but, assuming it to begin again at finger V, it proceeds by wire b to point B'. 110 Here it is broken again. It starts again from shaft L by wire c to magnet P, wire d, wire 35, and so back to battery. The break in the circuit between point B' and shaft L is normally closed by the spring-finger G on the 115 under side of escapement-disk K, resting in contact with said point B', so that circuit is thus established from point B' to finger G, to disk K, and so to shaft L. This leaves normally but one break in the circuit—that is, 120 between fingers V and W. Meanwhile the disk K is held at rest, because the escapement U is in the position shown in Fig. 9 and engages pin N, so that if now the fingers V W be brought into contact then the circuit 125 through magnet P will be completed, the armature Q will be attracted, the escapement U turned to the position shown in Fig. 10, and the disk will be allowed to turn until the pin N', Fig. 10, engages with escapement U; but 130 the disk in thus rotating carries the finger G on its under side out of contact with point B' and into contact with point B, and when the disk is arrested, as already described, the fin-

ger remains in contact with point B. The circuit from battery 36 then no longer includes wire 4, wire *a*, fingers V W, and wire *b*, but proceeds from battery by wire 37 to wire 3, 5 to wire *e*, to point B, and so to spring G, disk K, shaft L, magnet P, wire *d*, wire 35, and back to battery. Now, as the finger G passes from point B' to point B, circuit is broken and the magnet P releases its armature, so that 10 the escapement U now takes the position of Fig. 11, in which the pin N' is engaged with the inner periphery of the escapement U; but this condition remains only until the spring-finger G has met the pin B; but, as has already 15 been said, when the finger G meets the pin B circuit is completed again through magnet P; consequently that magnet again attracts its armature and brings the escapement U into the position shown in Fig. 11. Both pins N 20 N' are then released from the escapement, and the disk K is rotated onward by the action of its spring until the leading pin of the next pair, O O', meets the escapement; but as the disk K rotates the finger G leaves the 25 point B. Hence, circuit is broken through magnet P and its armature is retracted by the spring J, so that before the next pin reaches the escapement U said escapement is rotated from the position shown in Fig. 12 to 30 the position shown in Fig. 9. Suppose now that the finger G on disk K next makes contact with the pin C', Fig. 2. Then local circuit will be established from battery 36 by wire 37 to branch 4, wire *f*, pin C', finger G, disk K, 35 shaft L, and so to magnet P and back to battery, as before, and generally as the finger G touches each pin B B' C C', and so on, in succession, it will establish a closed circuit through magnet P, which will actuate the es- 40 capement U, in the manner already described, to cause the disk K first to rotate ahead a short distance equal to the interval between the pins N N', and, second, to rotate a long distance equal to that between each consecutive 45 pair of pins—as N N' and O O'. Now, referring to Fig. 2, it will be noticed that each pin B B' C' has an independent conductor leading to one or the other of the branches 3 or 4. Thus pin B connects with branch 3 by 50 wire *e*, pin B' connects with wire 4 by wires *b* and *a*, and pin C' connects with wire 4 by wire *f*. The other pins on the plate A in Fig. 2 are not shown connected; but in practice each pin, as in the preceding instances, would have its 55 own wire running to one or the other of the branches 3 or 4. It will also be observed that while the wires *e* and *f* connect to different branches the wires *a* and *f* connect to different points on the same branch 4. The object 60 of this will be understood from the following description of the general operation of the mechanism.

Suppose that a break occurs in the branch 4 at the point Y, Fig. 2. Magnet 5 will attract its armature and magnet 33 will release the motor mechanism of disk 21. The alarm-signal will pass upon main line, as already

described. As the disk 21 rotates, the stop 24 thereon is carried around to meet the inclined end of finger W, Fig. 1, and so to force said finger W into contact with finger V; but, although finger G of disk K is in contact with the pin B', circuit is not completed through magnet P because said circuit is broken at Y. Therefore the indicator-disk K will remain at 75 rest. But suppose that the circuit is broken 80 in branch 4 at the point X, Fig. 2, beyond the point of connection of wire *a*. Now, when the fingers V and W are brought into contact by the rotation of disk 21, circuit is completed 85 from battery through magnet P, which attracts its armature, releasing the escapement U, and the disk K moves ahead until its finger G leaves pin B' and strikes the pin B. The circuit which leads to pin B is closed 90 from branch 3, and hence the magnet P acts again, both pins B B' are passed by the finger G, which next makes contact with the pin C'; but the circuit leading to pin C' is broken at X; consequently the magnet P is not energized, the escapement is not moved, and the disk K stops. If the circuit leading to pin B had been broken, the disk would have stopped when its finger touched that pin. To express this in more general terms, as the 95 disk K rotates, its finger G sweeps over all the pins B B', C C', &c., and establishes circuit between each pin and magnet P, if it can. If, however, circuit is broken elsewhere, then when the finger G touches the pin connecting 100 with the ruptured circuit the magnet receives no current, and because it receives no current it fails to draw away the escapement, so as to let the disk K continue its rotation. Therefore the disk K stops. If, however, the 105 finger G as it feels the successive circuits finds them all intact, the disk K will make a complete revolution until the finger G once more meets the point B'. And here the disk K will 110 stop, because by the time this rotation has been effected the disk 21 will also have been rotated and the pin 24 thereon will have been carried out of contact with the finger W so that that finger will no longer make contact with finger V. Consequently fingers V and 115 W will separate, the circuit leading to pin B' will be broken automatically, and hence when the finger G touches pin B' magnet P will receive no current and the disk will stop.

In Fig. 8 I have illustrated my indicating 120 mechanism applied to a four-story building, and by following the various circuits here exhibited its operation will be clearly understood. The main line 1, dividing into the branches 34, proceeds up through the building, 125 the branches being on opposite sides thereof, and connects as before with the magnet 5. The wires 15 and 16 from this magnet proceed to the alarm mechanism, (here omitted for convenience,) and finally the main circuit is completed as before to wire 20 and line 2. It will be noticed that from the wires 34 in each story of the building wires lead to the pins B B' C C' D D' E E' of plate A. Thus, from wire 4,

in the first story, wire *a* leads to finger *W*, and thence the circuit proceeds to finger *V* and pin *B'*; from wire 3, in the first story, wire *e* leads direct to pin *B*; from wire 4, in the 5 second story, wire *f'''* leads to pin *C'*; from wire 3, in the second story, wire *f'* leads to pin *C*; from wire 4, in the third story, wire *g'* leads to pin *D'*, and from wire 3, in the third story, wire *g* leads to pin *D*. Finally, from 10 wire 4, in the fourth story, wire *h'* leads to pin *E'*, and from wire 3 wire *h* leads to pin *E*. In this way I guard both sides of each story of the building and I cause the indicator-disk to stop at the pin at which it finds broken circuit. 15 To illustrate—suppose circuit to be broken at *X*, left-hand side of fourth story. The disk *K* rotating, the finger *G* thereon will feel all the pins in succession, beginning with pin *B'*, and find circuit closed through all until it meets 20 pin *E*. Here the circuit would normally be from wire 3 to wire *h* to magnet *P*, wire *d*, battery-wire 35, battery 36, and wire 3 again; but this circuit is broken at *X*. Therefore the disk *K* will stop when its finger *G* touches 25 pin *E*. Any one skilled in the art will be able from Fig. 8 to note the effect of breaking the wire 3 or 4 at any point by simply tracing the circuit to the proper pin on plate *A*, and remembering that the disk *K* will stop when its 30 finger touches that pin.

It will be observed that each pair of pins, as *C C' D D'*, in Fig. 8, connect with the wires on opposite sides of each story. Consequently when the disk *K* stops at pin *C'*, for instance, 35 that indicates a break on the right-hand side of the story. If it stops at pin *C*, the fact that the break is on the left-hand side is shown. In order to indicate this conveniently, I affix to the face of the disk *K* at regular intervals 40 as many numbers 1 2 3, &c., as there are stories in the building, for example, as shown in Fig. 4. Then above this disk I arrange a fixed plate, *Z*, in which are two openings, *Z' Z''*, placed so that the indicating-numbers can be 45 successively seen through them as the disk *K* rotates.

As shown, the number 2 appears in the right-hand opening, *Z''*, and, referring to Fig. 8, this happens when the finger *G* on disk *K* 50 touches pin *C'*. If the disturbance had occurred on the left-hand side of the story, (second,) the number 2 would have appeared in the opening *Z'* and the finger *G* would have touched the pin *C*. This arrangement of the 55 indicator is of course arbitrary and may be varied to suit differing circumstances.

Returning now to Fig. 2, 43 is a branch wire extending from wire 37, and 44 a similar wire extending from wire 34. Wire 43 connects 60 with a bracket, 45. Resting upon the bracket 45 is a flat piece of insulating material, Figs. 6 and 7, 47 having a guide-slot, 48, which receives fixed guide-pins 49. Near one end of the piece of insulating material 47 is a slot, 65 50. On the inside edge of the door 7 is a spring-hook, 51½, which, when the door is closed, engages in slot 50 and moves the piece

of insulating material 47 between the spring-finger 46 and the top of the bracket 45, thus 70 breaking circuit through the shunt 43 45 46 44, as shown in Fig. 7. When the door is opened, the hook 51½ draws the piece of insulating material 47 from between the spring-finger 46 and bracket 45, and thus allows said finger to meet said bracket, and so establish 75 circuit through the aforesaid shunt. The effect of thus establishing circuit is to energize magnet 33 and start the alarm. In this way any tampering with the apparatus is prevented inasmuch as it is necessary to open 80 the door to get access to the mechanism, and the operation of opening the door causes an alarm-signal, as above explained, to be transmitted. The said hook 51½ is simply a spring-hook secured to the inside edge of the cover, 85 and when the latter is closed the hook springs into the slot 50 and operates the sliding insulator, and when the cover is opened it draws upward on the sliding insulator until the latter is stopped by the pins 49, when it (the 90 hook) will spring out of engagement and allow the door to open.

The rotation of the disk 21, Fig. 1, is limited by the stop 24, which finally comes in contact with the lower side of the arm 22, and so 95 prevents further revolution of the disk.

The object of supporting the magnet 5 and standard 12 upon the spring-arm 8 is to prevent the armature of the said magnet from closing contact with the plate 13 by any jar-ring of the box 6.

In another application for Letters Patent filed simultaneously herewith, Serial No. 265,813, I have fully described the alarm mechanism and the spring-supported magnet 105 5 herein set forth. My present application is limited to the indicator apparatus individually and in combination with the said alarm mechanism. The subject-matter of the claims of my said other application are herein 110 disclaimed.

I claim—

1. The combination of the battery 36, fixed contact *B'*, a circuit-closer, *V W*, interposed between said battery 36 and contact *B'*, spring-actuated wheel 21 for closing the circuit-closer, an electro-magnet in circuit with battery 36 for automatically releasing the wheel 21, disk *K*, carrying finger *G*, and mechanism (as spring 1) for rotating said disk, electro-magnet *P*, having armature *Q*, and escapement *U*, actuated by said armature and moved thereby into and out of engagement with said disk *K* to arrest or release the same, substantially as described. 125

2. The battery 36, and in branch circuit therewith a fixed contact, *B'*, a circuit-closer, *V W*, interposed between said battery 36 and contact *B'*, a spring-actuated wheel, 21, for closing the circuit-closer, an electro-magnet 130 in circuit with battery 36 for automatically releasing the wheel 21, and in a second branch circuit with said battery a fixed contact, *B*, in combination with the disk *K*, car-

rying finger G, and mechanism, as spring I, for rotating said disk and moving said finger into successive touch with said contact-points, electro-magnet P, having armature Q, and escapement U, actuated by said armature and moved thereby into and out of engagement with said disk K to arrest or release the same, substantially as described.

3. A line-wire, an electro-magnet having two oppositely-wound coils included, respectively, in branch circuit with said line-wire, a circuit-closer, mechanism for automatically operating said circuit-closer, a stop or detent arresting the motion of said mechanism and controlled to release the same by said electro-magnet, in combination with a battery, a fixed contact, the said circuit-closer, a movable contact, and an electro-magnet, (the said parts being in local circuit,) mechanism for moving said movable contact into touch with said fixed contact, an armature actuated by said electro-magnet, and a stop or catch actuated by said armature and moved thereby into and out of engagement with said movable contact mechanism to arrest or release the same, substantially as described.

4. The combination of a line-wire, an electro-magnet having two oppositely-wound coils, an armature actuated by said magnet, two branches from said line-circuit, including said coils, a series of branches extending from each of the aforesaid branch circuits and ter-

minating in fixed contact-points, a circuit-closer in one of said branches actuated by the armature of said electro-magnet to open or close circuit, a movable circuit-closer and mechanism for moving the same successively into contact with each of said fixed contact-points, an electro-magnet, an armature therefor, a stop or catch actuated by said armature and thereby moved into or out of engagement with said movable circuit-closer, and a local battery, the said local battery including in its circuit the said branches, fixed contactpins, movable circuit-closer, and electro-magnet, substantially as described.

5. The line-wire 1, 2, having branches 3, 4, electro-magnet 5, having oppositely-wound coils included, respectively, in said branches, armature 11 of said magnet, rotary disk 21, 50 having pin 23, and mechanism for actuating the same controlled by said armature 11, in combination with the local battery 36, having in one branch circuit the fingers V, W and pin B', and in second branch circuit pin B, 55 and in main circuit rotary escapement-disk K, carrying contact-finger G, and the electro-magnet P, the said electro-magnet having armature Q, and the escapement U, actuated by said armature, substantially as described.

WILLIAM A. BARNES.
